[57]

ABSTRACT

Device for time sequencing the starting and stopping of separate groups of operating elements at adjustable time intervals, upon starting and finishing the operation of textile machines, such as open end spinning machines in which mass piecing is performed by reversing the run of both the withdrawing and the winding elements by means of an electrical control mechanism provided with a plurality of switch elements each of which is operatively associated with a respective group of spinning units and each of which is adjustable to determine the time of operation of its respective group of operating elements for such spinning units. For each of the switch elements there is at least one driven control element the motion of which is derived from one of the common driven elements of the machine via an electromagnetically controlled clutch. The control elements include axially displaceable cams for operating the respective switches. Each control element is selectively disengageable from its driving means to permit its separate time adjustment.

DEVICE FOR SEQUENTIAL STARTING AND STOPPING SEPARATE GROUPS OF OPERATING MEANS IN ADJUSTABLE TIME INTERVALS

The present invention relates to a device for sequentially starting and stopping separate groups of operating means in adjustable time intervals as for example, in the starting and stopping the operation of textile machines, particularly open end spinning machines, in which mass piecing is performed by reversing the run of the withdrawing and winding means by an electrical control mechanism provided with switch elements each of which is operatively associated with a respective group of spinning units and each of which is adjustable to determine the time of operation of its respective group of operating elements for such spinning units.

In open end spinning machines which comprise a plurality of spinning units arranged beside one another on one or on both sides of the machine, a re-starting after stoppage is required which disturbs the spinning process to a minimum extent. For that reason, it is necessary to perform a certain number of predetermined operations in a precise time sequence, by means of which the spinning process being performed in the separate spinning units is continuously finished and, upon re-starting the machine, continuously started. The necessary sequence of the said operations, particularly their repetition with high operating speeds which are also determined by the kind of fibrous material processed and the quality of the final product, i.e., the yarn, requires an accurate and fast starting and finishing of each operation in the given sequence with a minimum time delay. Thus, e.g. upon machine stoppage it is necessary first to interrupt the feeding of fibrous material into the spinning chamber, to process to yarn the rest of the fibrous material still present inside the spinning chamber, and thereafter to stop the yarn withdrawing and winding elements at the moment at which the yarn end leaving the spinning chamber is still under the influence of vacuum exerted by the spinning chamber during its operation, i.e., at the moment at which the yarn end has not yet left the opening for withdrawing yarn from the spinning chamber.

Upon re-starting the operation of the machine, it is necessary to re-start the operation of the yarn withdrawing and winding elements, at first in a direction opposite to that of normal operation, whereby the yarn end is reintroduced into the spinning chamber, which is already in operation and into which the feeding of separate fibers is re-started at an adjusted rate of feeding. At the moment at which the yarn end comes into contact with the separate fibers deposited on the collecting surface of the spinning chamber, the direction of driving of both the withdrawing and winding elements must be reversed, the spinning process being thereafter continued in the normal sequence.

The time sequencing of the separate steps mentioned above is automatically performed in devices hitherto known by means of power controlled mechanical means which perform said steps at predetermined time intervals.

A device is known for controlling this process of so-called mass piecing; this device consists of a combination of time and switching relays which cooperate with electromagnetic brains and clutches. The disadvantage of those elements used for the said process consists in their dependence on the accuracy of their adjustment;

this however, have certain inherent variations due to temperature and voltage even in well adjusted relays. The reduced reliability of devices of that type is also caused by the machine as such, such machine having 5 different starting characteristics depending upon its temperature as well as upon its environment and also on its own constructions and particularly on its condition.

These disadvantages can be mitigated by another 10 known device for controlling the mass piecing process, in which a system of switches is used, said switches being adjustably distributed on a disc within the circular path of a rotating finger or dog driven by the main motor of the machine via a clutch. The distances between said switches determine the time of the reverse running of the withdrawing and winding elements, i.e., the driving cylinders or shafts which are common for the whole machine. In other words, the timing during 15 which the yarn has been returned into the spinning chamber, as well as the time necessary for processing the rest of the fibrous material which at that time is still in the spinning chamber. In the event that the power supply from the power network is interrupted for whatever reason, a so-called stop relay in said device responds thereto, said relay due to voltage loss, interrupting its connection with the power supply network and thus starting the course of operations for stopping the machine in the proper time sequence. The operating 20 elements for performing this sequence of operations are supplied by the necessary power from an auxiliary source of power, which in the described apparatus is formed by capacitors. In other known devices of that 25 type, said auxiliary power source is constituted by a rotating electric machine, e.g., an AC-generator or a DC generator, using the run-out of the working machine as such and being connected to an electric circuit in which there are further connected two control devices for the direct control of the separate mechanisms of the 30 spinning units.

The main disadvantage of the above-mentioned device, in which the control of the mass piecing is performed by adjustable switches controlled by a rotating finger or dog driven from the main motor of the machine, is that a certain percentage of accuracy is 35 achieved which, however, cannot overcome the difficulties in mass piecing due to the limited extent of the adjustability of the device, which is determined by the arrangement of the switches and the dimension of the disc on which said switches are arranged. This limited 40 accuracy of the device results in inaccuracies in inducing impulses for the separate control mechanisms, such inaccuracies disturbing the continuity of the mass piecing process.

55 The device according to the present invention has among its objects substantially to mitigate the mentioned disadvantages of the devices hitherto known by making possible a simple and accurate adjustment of the time intervals necessary for starting and stopping the separate groups of operating means of the open end spinning machine in a time sequence which is necessary for stopping and restarting of the spinning process in this machine.

In the device according to the present invention, 60 each of the switch elements has at least one control element the motion of which is derived from one of the common elements of the machine via a clutch.

One advantage of the device according to the present invention is that it is possible to eliminate both electrical and mechanical assemblies which previously caused failures upon mass piecing; another advantage of the device according to the present invention is that it makes possible an accurate and easy adjustment, i.e., a programming of all operations, particularly their sequence in accurate time intervals, whereby an accurate and fast yarn piecing is achieved with the elimination of time losses, the use of said device results in the higher quality of the final product, i.e., the yarn and the simultaneous increase of the productivity of the spinning machine.

Further advantages and features according to the present invention are described in the following specification and shown in form of an embodiment in the form of example in the accompanying drawings, of which:

FIG. 1 is a perspective view of the arrangement of the common parts of an open end spinning machine together with the device according to the present invention:

FIG. 2 is a detailed section of the device according to the present invention in side view; and

FIG. 3 is a detailed view in front elevation of the device according to the present invention.

In FIG. 1 there is shown an open end spinning machine which is provided with a plurality of spinning units 1 (one shown) arranged in a row on one or both sides of the machine. The machine is equipped with common driven elements 2, 3, 4, e.g. in form of cylinders or shafts, of which element 2 performs the feeding of fiber 5 into the spinning units 1, element 3 performs the withdrawal of yarn 6 from the spinning units 1 and element 4 performs the winding of said yarn 6 onto bobbin 6'. The said driven elements 2, 3, 4 are arranged along the whole length of the machine and end at side wall 12 of the machine in means of transmitting rotary motion to them from the main driving source of the machine, i.e., from an electric motor 9 mounted in the lower part of the machine. For clarity of illustration in FIG. 1 there is shown only the transmission of rotary motion to driven element 4 by means of a gear 8 connected by a driving belt 8 with electric motor 9 and meshing with a gear 7 fixedly connected to the end of driven element 4. Gear 7 also meshes with a gear 10 which transmits rotary motion to a control device 11 according to the present invention. Device 11 is fastened in a conventional manner to side wall 12 of the machine.

The control device 11 FIGS. 2 and 3 has a circular body 13, in the center of which there is mounted an electromagnetic clutch having two parts 141, 142, formed by clutch wheels, which are provided with confronting selectively meshing gear teeth 151, 152, respectively. Clutch 141, 142 is rotatably mounted on a shaft 16, which passes through the body of an electromagnet 17', the end of shaft 16 is mounted in a lid or cover 18 connected to the circular body 13. The part 141 of the electromagnetic clutch is also the armature of an electromagnet 17 and is axially displaceable on shaft 16, its motion being controlled by means of the electromagnet 17 which is controlled by a control mechanism (not shown). A coil compression spring 19 is mounted upon shaft 16, such spring constantly urging clutch part 141 into mesh with clutch part 142 in its operative position i.e., when clutch 141, 142, is in opera-

tion and electromagnet 17 does not act upon the first wheel 141 of said clutch. Beside the already mentioned gear-teeth 151, 152, respectively of the two wheels 141, 142 of the clutch, the parts of said clutch have radial ring gears 201 and 202, respectively connected thereto. The radial gear 202 on the second wheel 142 of the clutch is in mesh with a transmission gear wheel 21 which is fastened on shaft 22, shaft 22 is rotatably mounted in lid 18, said transmission wheel 21 being inside lid 18 and the driving transmission wheel 10 affixed to shaft 22 being outside lid 18.

The radial gear 201 of the first wheel 141 of the clutch is in mesh with a plurality of transmission gears 23 fastened to shafts 24 rotatably mounted in bearing sleeves 25 on body 13 and evenly angularly spaced about the axis of shaft 16 on a radius corresponding to the distance between the center of the first wheel 141 of the clutch and the transmission gears 23. On the other end of shafts 24, there are fastened control elements 26, each in the form of a disc with a projection or cam lobe 40 thereon. Equally angularly spaced about device 11 there are mounted switches 271, 272, 273, 274 (FIG. 3) for closing the separate electric circuits of a control mechanism (not shown) for controlling the time sequence of the separate operations which take place upon the starting and stopping of the machine. The said switches 271, 272, 273, 274 which have operating arms 41, are fastened on an annular part of the fixed body 13. The elements 26, which have the above mentioned cam lobes 40 thereon, are provided on their front parts with thumb knob extensions 28 for adjusting the position of the cam lobes 40 on control elements 26.

The disc surface of each control element 26 is provided with an inspection hole 30 through which there are visible digital symbols on a scale 29 which is arranged on gear 21 rearwardly of the respective control element 26. Near each inspection hole 30 there is an index mark 31 on the disc surface of control element 26, said index mark cooperating with the scale 29 to permit the visual control of the adjustment of the control element 26. As above explained, the transmission wheel 23 of each control element 26 in operative position is in engagement with the first wheel 141 of the clutch and is secured in this position by means of a coil compression spring 32 mounted on shaft 24 between the control element 26 and the bearing sleeve 25. On that side (left, FIG. 2) of device 11 on which the control elements 26 are mounted there is a transparent housing 33 through lobes in which there project extensions 28 for the adjustment of the control elements 26.

The device according to the present invention operates as follows:

Upon operation of the units 1 of the open end spinning machine, the first wheel 141 of the clutch is in mesh with gear wheels 23, the gear teeth 151 of said first wheel 141 of the clutch being out of engagement with the gear teeth 152 of the second wheel 142 of clutch; said wheel 142 of the clutch rotates during the whole time of machine operation since it is permanently connected to a direct transmission of the drive of either the winding cylinder 4 or the withdrawing cylinder 3.

Upon starting the machine by an appurtenant mechanism for controlling mass piecing, the electric circuit of electromagnet 17 is interrupted, whereupon the gear-teeth 151, 152 of the clutch wheels of the clutch are

thrust into engagement by spring 19 and drive the control elements 26 of the device control 11. Control elements 26 in the adjusted time sequence selectively close and open the contacts of switches 271 to 274. As we have seen, switches 271-274 control the reverse motion of the withdrawing cylinder 3 and the winding cylinder 4, the feeding of fibrous material 5 by cylinder 2, and the change of the original normal direction of rotation of the winding cylinder 4 and the withdrawing cylinder 3 to the reverse direction in which yarn 6 is withdrawn from spinning unit 1 and is wound on to bobbin 6'.

Upon initiation of the process of mass piecing, the direction of driving both the winding cylinder 4 and the withdrawing cylinder 3 is reversed, and thus the yarn end 6 is reintroduced into the spinning chamber where it contacts the fiber deposited in the form of a ribbon on the collecting surface of said spinning chamber in spinning unit 1. At the moment of contact of yarn end 6 and the fiber ribbon in the spinning chamber of spinning unit 1, the direction of rotation of withdrawing cylinder 3 and winding cylinder 4 is changed back into the original direction of rotation, yarn piecing takes place, and the spinning process is carried on in the usual manner.

In the event that the machine is stopped by the attendants or upon stoppage of the machine for whatever unforeseen reason (e.g. interruption of power supply from the supply network), electromagnet 17 obtains an impulse from the contact of an auxiliary relay (not shown), by means of which its connection to the appurtenant electric circuit is interrupted. Thus the electromagnet is then deenergized, and the pressure spring 19 causes the teeth of the wheels of the clutch to engage, whereupon rotary motion is transmitted from the wheel 141 of the clutch to the transmission wheels 23 of control elements 26, the switch operating cam lobes or projections 40 of which begin to move in a circular path, so that the contacts of switches 271, 272, 273, 274 are closed by the interaction of the cam lobes 40 and the switch arms 41 at a certain preadjusted positions in determined time intervals and in the desired time sequence.

When the necessity of readjustment of any time interval or time sequence arises, which is necessary for performing a certain operation upon starting or ending the operation of the open end spinning machine either depending upon the kind of fibrous material to be processed, the required yarn number, or any other reasons which determine the securing of the correct course of the spinning process, it is possible either during machine operation or even before starting its operation to disengage the transmission gear wheel 23 of the appurtenant control element 26 from the first wheel 141 of the clutch by pressing thumb knob 28 inwardly and turning the control element 26 and thus its cam lobe 40 in the required direction. By this step the appurtenant time interval for any control element 26 for any of

switches 271, 272, 273 274 is extended or shortened for the separate operation necessary for starting or finishing the operation of the open end spinning machine. By releasing the pressure acting upon thumb knob 26, transmission wheel 23 is again in engagement with the first wheel 141 of the clutch, whereby the adjustment of the appurtenant time interval is completed.

Although the invention is illustrated and described with reference to one preferred embodiment thereof, it is to be expressly understood that it is in no way limited to the disclosure of such a preferred embodiment, but is capable of numerous modifications within the scope of the appended claims.

What is claimed is:

1. In an open end spinning machine having a plurality of groups of open end spinning units, each such group having means for withdrawing yarns from the spinning units of such group and means for winding the yarns withdrawn from the spinning units of such groups, and common driving elements for the yarn withdrawing and winding means of each such group, a common element for driving the yarn withdrawing and yarn winding means of each group of spinning units, mass piecing being performed by reversing the run of both the yarn withdrawing and the yarn winding elements, the improvement which comprises electrical controlled mechanism provided with a plurality of switch elements, each switch element being operatively associated with a respective group of spinning units and each switch element being adjustable to determine the time of operation of the yarn withdrawing and the yarn winding means of the respective group of spinning units, at least one driven control element for each of the switch elements, means for driving the control elements from one of the common driving elements and a controllable clutch interposed between said one of the common driving elements and said control elements.

2. The combination according to claim 1, wherein the clutch is an electromagnetic clutch, and comprising further switch means associated with the spinning machine for controlling the clutch.

3. The combination according to claim 1, wherein the control elements are axially displaceable cams, of said cams, each being connected in its operative position through the clutch to said one of the common driving elements.

4. The combination according to claim 3, comprising a separate set of selectively meshing gears serially interposed between the clutch and each control element, and resilient means constantly urging the control elements to their axial position in which the gears of said separate gear sets are in mesh.

5. The combination according to claim 1, wherein the control elements are driven by the common driven element which drives the yarn withdrawing means.
